UNITED STATES PATENT OFFICE.

ISIDORE LEGAY, OF NEW YORK, N. Y.

HEEL-BURNISHING MACHINE.

SPECIFICATION forming part of Letters Patent No. 298,484, dated May 13, 1884.

Application filed October 17, 1883. (No model.)

To all whom it may concern:

Be it known that I, ISIDORE LEGAY, of the city, county, and State of New York, have invented a new and useful Improvement in Heel-Burnishing Machines; and I do hereby declare that the following is a full and exact description thereof, reference being had to the accompanying drawings, and to the letters of reference marked thereon, making a part of this specification.

My invention relates to that class of shoe-heel-burnishing machines, in which the shoe is supported upon an oscillating shaft in suitable position to bring the heel of the shoe in line for contact with an adjustable burnishing or finishing tool.

The object of my invention is, first, to facilitate the attachment of the shoe to the oscillating shaft; second, to produce an automatic bearing of the burnishing-tool upon the heel; and, third, to permit the tool and its guide and frame to be swung out of the way, so that the burnished heel may be readily finished upon the machine by an application of hand-tools where required; and it consists in the construction and adaptation to these ends of the mechanism hereinafter described and claimed.

In the accompanying drawings, Figure 1 is a perspective view of my improved machine complete. Fig. 2 is an enlarged view of the burnishing-tool, and Fig. 3 is an elevation of the movable stay-block which actuates the burnisher and its gearing detached.

A A' A' represent a suitable base and standards, upon which is mounted an oscillating shaft, B. An oscillating movement is imparted to this shaft B by means of a cog-wheel, C, fitted thereon, and which is interposed between toothed racks D D', adapted to reciprocate freely between suitable vertical guides arranged on opposite sides of the wheel, and to engage the same. To one of these racks, D', is suspended a weight, D''. The lower end of the opposite rack, D, is connected by means of a cord or rod, D', with a treadle, E. The pressure of the operator's foot, when applied to the treadle E, will serve to counter-balance the suspended weight D'', and to produce, by the operation of the treadle, an alternate reciprocation of the two racks D D', which will operate to produce an oscillation

of the shaft B. One end, B', of the shaft is made to project beyond its bearings, and upon this projecting end is fitted a sliding collar, F, carrying a dog or clamping-arm, F', adapted to project beyond the end of the shaft, in line parallel therewith, and which is so bent, as shown in Fig. 1, as to permit of the insertion of a shoe upon the end of the shaft 60 inside of said arm. The free end of the clamping-arm or dog F' is carried upward, so as to bring it into line with the axis of the shaft, and it terminates in a threaded nut, F'', through which works a threaded clamping-bolt, F', whose axis coincides with the axis of the shaft B. The end of this clamping-bolt F' projecting toward the main shaft terminates in a disk presenting a flat surface perpendicular to its axis. The opposite end of the bolt is fitted 70 with a crank or hand-wheel, F', for its rotation. The sliding collar F, by which the dog or clamping-arm is supported upon the shaft B, is secured, when adjusted, by means of a set-screw, F'.

The burnishing-tool and the movable stay-block by which its position upon the heel is adjusted are supported by means of a frame carried upon the upper free end of an arm, G, pivoted to swing in a plane at a right angle 80 to the axis of the shaft B upon a vertical rod, G', mounted upon a standard, G'', supported upon the base A of the machine in line with the standards A' A', and the oscillating shaft B, supported thereby. The rod G' is made 85 adjustable vertically in the standard G'' by means of a capstan-headed screw, a, fitted to the lower end of the rod with a socket-joint, and which works in a tubular threaded seat or recess in the upper end of the standard. 90 The arm G is guided in its vibration by means of a plate, G', attached at its lower end to the upper end of the vertically-adjustable rod G' in a plane at right angles to the axis of the shaft B, and against which the arm swings 95 under a parallel bar, b, secured to the upper end of the plate, as illustrated in Fig. 1, the arm being pivoted at its lower end to the face of the plate G', immediately over the top of the rod G', so as to admit of being brought 100 into a vertical position coincident with the axis of said rod and in line with the axis of the shaft B, and to swing out thence to an angle of forty-five degrees, more or less. The

guide-plate G⁴ is secured and supported not only by its attachment to the adjustable rod G², but also by means of horizontal brace-rods c c, secured at one end to the adjacent stand- 5 ard A', and at the other to the plate, the vertical adjustment of the latter being provided for, either by the use of elastic brace-rods or by passing the end of the rods through slotted apertures c' c' in the plate, as illustrated 10 in Fig. 1.

Upon the upper end of the swinging arm G a shaft, H, is mounted in suitable bearings parallel with the shaft B, and by the vibration of the arm G this shaft may be brought into 15 a position directly over the prolonged axis of the shaft B. Upon the body of this shaft H is mounted a cog-wheel, I, firmly attached thereto, and the face of this wheel, in line parallel with its axis, is equal to or greater 20 than the height of the shoe-heels to be burnished. The shaft H is adapted to traverse longitudinally in its bearings, and it is threaded at its inner end to engage a threaded seat in its inner bearings, so that it shall be fed for- 25 ward or backward therein by its simple rotation. Its rotation is produced by means of a second cog-wheel, J, of a larger diameter than the cog-wheel I, and which is mounted in the same frame to gear into said wheel, and is 30 actuated by means of a hand-wheel or crank, J², placed upon the end of its shaft.

A stay block or plate, K, is supported upon the ends of two parallel rods, K' K', which are arranged to slide in line parallel with the shaft 35 H through bearings in the frame which carries the wheels I and J. This block K is moved backward and forward over the heel of the shoe, when it is clamped to the end of the main shaft B, by the reciprocating move- 40 ment of the screw-shaft H, whose inner end engages a socket in the end of the block.

Attached to the frame upon the upper end of the arm G, and projecting upward therefrom, is an arm, L, terminating at its upper 45 end in a threaded nut, L', through which works a transverse bolt, M. Upon one end of this horizontal bolt is formed a hand-wheel, M', and to its opposite end an annular plate or disk, M², is attached with a pivot-joint. (See 50 Fig. 1.) Through this annular plate M², as a collar, a weighted rod, N, passes loosely, and terminates at its lower end in a weight, N', in the lower side of which is formed a socket adapted to receive the shank of the burnishing- 55 tool O. By an adjustment of the weighted rod N and of the horizontal screw-bolt M the disk M² may be brought in proper position over the heel of a shoe clamped upon the end of the main shaft B, so that the tool will drop 60 and rest automatically with its full weight upon the heel.

The burnishing-tool O, Fig. 2, is formed of a flat rectangular piece of metal provided with a shank projecting from its upper edge, to permit of its attachment to the rod N, its opposite edge being cut to form a V-shaped re-entering angle, the inner surfaces of the V being made

smooth and the angles neatly rounded, to present a polishing-surface to the heel to be operated upon.

In operating my improved machine the shoe, either with or without a last, is placed over the projecting end B' of the main shaft B, with the heel out, and the clamping-arm or dog F' is moved inward until the disk on the end of its clamping-bolt F² rests against the outer end of the heel of the shoe. The clamping-arm is then made fast by means of the set-screw F³. The bolt F² is then screwed up until the shoe is firmly held against the end of the main shaft, so as to rotate therewith. If, now, the arm G be swung into position to bring the burnishing-iron O, clamped to the weighted rod N, in position, with its V-shaped notch embracing and resting upon the front edge 85 of the heel of the shoe, and the movable stay-block K is carried forward against the lower end of the burnisher O as it thus rests on the edge of the heel, the machine is ready for the operation of burnishing. An oscillating motion being imparted to the main shaft B by means of the treadle and the racks D D', the shoe is made to rotate reciprocally, the burnisher bearing thereon with its full weight added to that of its weighted rod N. Mean- 90 time the burnisher is made to traverse backward and forward upon the heel by means of the plate or rest K, which, being carried forward by the rotation of the screw-shaft H through the agency of its operating-wheels I 100 J and crank J², will move the burnisher back over the heel, and, being withdrawn, will allow it to slide forward by reason of its weight over the slope of the heel. When the heel is sufficiently polished by the burnishing-iron, 105 the latter is removed, and the arm G, carrying the stay-plate K, is unclamped and swung back out of the way, so that a finishing-tool may be applied by hand to the still rotating heel.

I reserve the right to cover the burnishing-tool formed with a V-shaped recess in its lower edge, to rest upon and embrace the curve of the shoe-heel, in a future application for Letters Patent; and

I claim herein as my invention—

1. In a shoe-heel-burnishing machine, the combination, with the oscillating main shaft, of an adjustable shoe clamp or dog fitted upon the end of said shaft by means of a sliding collar encircling the shaft and fixed by a clamping device, substantially in the manner and for the purpose herein set forth.

2. In a shoe-heel-burnishing machine, a shoe clamp or dog secured by one arm to an adjusting-collar encircling the oscillating main shaft of said machine, and carrying upon its opposite arm a screw-bolt terminating in a face-plate, and fitted to traverse in line with the axis of the shaft through a fixed nut on the end of the arm, and to be actuated for adjustment by a suitable crank or hand-wheel, substantially in the manner and for the purpose herein set forth.

3. In a shoe-heel-burnishing machine, the

- combination, with its oscillating shaft and shoe-clamping device, of a toothed wheel upon said shaft, a weighted reciprocating rack engaging the same upon one side, and a corresponding rack engaging its opposite side, and actuated by a suitable prime motor for the purpose of imparting an oscillating motion to said shaft, substantially in the manner and for the purpose herein set forth. 5
4. In a shoe-heel-burnishing machine, a weighted burnishing-tool supported loosely in a vertical plane coincident with the axis of the oscillating shaft, so as to drop automatically upon the heel of a shoe clamped upon and oscillating with said shaft, substantially in the manner and for the purpose herein set forth. 10
5. In a shoe-heel-burnishing machine, the combination, with a weighted burnishing-tool 20 adapted to rest and bear automatically upon the heel of a shoe carried by the oscillating shaft of the machine, of a stay-block adapted to traverse at right angles to the burnishing-tool, and to bear against the face thereof to steady it and cause it to move back over the heel, substantially in the manner and for the purpose herein set forth. 25
6. The combination, in a shoe-heel-burnishing machine, with its weighted automatic
- burnishing-tool, and with a stay-block traversing at right angles to the tool, to bear against the face thereof, of a screw-shaft engaging said stay-block and working through a threaded seat in a fixed bearing, an extended pinion secured upon the shaft, and a toothed wheel 30 engaging said pinion and rotating in fixed bearings, substantially in the manner and for the purpose herein set forth. 35
7. The combination, in a shoe-heel-burnishing machine, with its burnishing-tool and the bearings supporting the same, and with a stay-block traversing at right angles to said burnishing-tool, and the bearings supporting the same, of a vibrating arm carrying and supporting upon its upper end the bearings of the 40 burnishing-tool and its stay-plate, and which is pivoted at its lower end to an adjustable standard in line with the oscillating shaft of the machine, to vibrate in a plane at right angles thereto, substantially in the manner and 45 for the purpose herein set forth. 50

In testimony whereof I have signed my name to this specification in the presence of two subscribing witnesses.
